UNITED STATES PATENT OFFICE.

HENRY CHARLES PLATTS AND THOMAS LAWTHER, OF LONDON, ENGLAND.

STEAM-BOILER.

SPECIFICATION forming part of Letters Patent No. 651,269, dated June 5, 1900.

Application filed June 29, 1899. Serial No. 722,294. (No model.)

To all whom it may concern:

Be it known that we, HENRY CHARLES PLATTS and THOMAS LAWTHER, subjects of the Queen of Great Britain and Ireland, residing at Lime street, London, England, have invented Improvements in Steam-Boilers, of which the following is a specification.

This invention has reference to steam-boilers of the kind in which there are located within the water-containing shell of the boiler a furnace tube or flue, or more than one, containing the fire grate or grates and one or more other tubes or flues through which the products of combustion and hot gases after leaving the furnace or furnaces return to or toward the front of the boiler; and our object is to so construct and arrange such boilers as to improve the water circulation therein and to utilize the gases flowing through the return flue or flues and whose temperature is lower than that of the products of combustion and gases within the furnace flue or flues for imparting heat to the cooler water within the boiler instead of allowing said products of combustion and gases to pass, as heretofore usual, through parts of the boiler (and especially those parts immediately above the furnace flue or flues) containing more highly-heated water, whose temperature is liable to become thereby lowered rather than raised in consequence of the water surrounding the return flue or flues sometimes having a higher temperature than the products of combustion and hot gases passing therethrough.

In carrying out this invention the furnace tube or flue (hereinafter called the "furnace-flue") or each of them, if there be more than one, and the return tube or flue or return tubes or flues (hereinafter called the "return" flue or flues) is or are so relatively arranged within the shell of the boiler that the return flue or flues shall not be, as is usual, above, or to a large extent above, the furnace flue or flues, and consequently in the hottest parts of the boiler, but wholly or mainly either at one or both sides of or below or at one or both sides of and below the highest part or parts of the furnace flue or flues, the arrangement being such that the water in contact with the return flue or flues shall be the less-heated portions of the water in the boiler and such as will usually on coming into contact

with the wall or walls of the return flue or flues be at a lower temperature than the products of combustion and hot gases then passing through the return flue or flues.

When one or more return-flues of large diameter or width is or are employed, we sometimes arrange within it or them other tubes open at their ends to the water-space of the boiler, so that water circulating through these tubes may have its temperature raised by the products of combustion and hot gases impinging upon the exteriors of the tubes during their passage through the return flue or flues.

In order that others skilled in the art may be enabled to make and use our said invention, we will now more particularly describe the same, with reference to the accompanying illustrative drawings, in which—

Figure 1 shows, partly in front elevation and partly in cross-section on the line *xx* of Fig. 2, a steam-boiler embodying this invention and having a centrally-arranged furnace-flue with a return-flue at each side provided with curved water-tubes. Fig. 2 shows a horizontal section of same on the line *yy* of Fig. 1. Fig. 3 shows a cross-section of a modified construction in which the furnace-flue occupies a lower position in the shell. Fig. 4 shows a similar view of another modified construction comprising one furnace-flue and to one side thereof one return-flue. Fig. 5 shows a similar view of another modified construction comprising two furnace-flues, one cylindrical return-flue, and the curved return-flues.

In all the examples like parts where they occur are marked with the same reference-letters.

Referring to Figs. 1 and 2, *a* is a cylindrical outer shell within which there is concentrically placed a cylindrical furnace-flue *b*, corrugated or not, and having within it a grate or grates *c*, with the necessary bridge *d*, or bridges, said shell being, as well understood, set in suitable brickwork *e*, with appropriate flues, such as *f*, leading to a chimney *g*. Within the annular space *h* between the exterior of the furnace-flue *b* and the inner surface of the shell *a* there are provided at two opposite sides of the boiler a couple of return-flues *i*, whose upper and lower ends *j* constitute tube-plates, which in the example are in

planes radiating from the axis of the furnace-flue, (though this direction is not in all cases essential,) while the outer and inner walls of the said return-flues constitute arcs of circles whereof the axis of the furnace-flue is or 5 may be the center. The upper tube-plate *j* of each return-flue *i* is at its highest part not above the level of the highest part of the furnace-flue *b*. Within the return-flues *i* there 10 are water-circulating tubes *k*, whose ends are suitably fixed in the respective tube-plates *j* of those flues, these water-tubes *k* having their axes in circular arcs struck (in the example) from the axis of the furnace tube or 15 flue *b*. The distance apart of the two top tube-plates *j* is made greater than the length of the longest water-tubes *k*, so that such tubes can when necessary be moved into the space between the said tube-plates and then 20 be withdrawn through a manhole in the top of the boiler-shell. The return-flues *i* may be suitably stayed to the furnace-flue *b* and to the shell of the boiler. In the example 25 shown they are simply stayed or stiffened by stays *l* of T-section, but other suitable stays may be substituted. Products of combustion and hot gases from fuel on the grate *c* pass along the furnace-flue *b* to the space or chamber *n*, thence dividing and passing in the re- 30 verse direction partly through each of the side return-flues *i*, in passing through which the hot gases impinge upon the tubes *k*, thereby imparting heat to water therein which circulates through said tubes toward other parts 35 of the boiler, cooler water from the lower parts of the boiler ascending within said tubes to replace that which passes out at their upper ends. The water-circulating tubes *k* instead of being curved and connecting the top 40 and bottom of each flue may be straight and arranged to connect the sides of the flue, as shown in dotted lines in Fig. 1, such tubes then serving also as stays to the sides of the flue. Thus it will be seen that by our inven- 45 tion we are enabled to utilize to the best ad- vantage products of combustion and hot gases that have already imparted some of their heat to water in higher parts of the boiler during their passage through the furnace-flue *b*, be- 50 cause we apply these now comparatively less heated gases in parts of the boiler where, as is well known, the temperature of the water is lower than it is in immediate proximity to those parts of the furnace-flue against which 55 the products of combustion and hot gases in the first instance more directly act.

As will be evident, this principle of construction of boilers, according to which the return-flues are located within those portions 60 of the shell wherein the water is not brought into proximity to the effective heating-surface of the furnace flue or flues, may be em- bodied in a variety of forms without depart- 65 ure from the characteristic features of our invention. Thus it will be obvious that in the example illustrated in Figs. 1 and 2 the details of the boiler itself and of its setting

may be varied, the cross-sectional form of the return-flues might be more or less altered, and also the number, form, and direction 70 of the water-tubes, which in some cases might even be dispensed with.

According to the modification represented in Fig. 3 the furnace-flue *b* is so fixed within a cylindrical shell *a* that the axis of said flue 75 is below that of the shell, and at the respective sides there are provided between the furnace tube or flue *b* and the shell *a* return-flues *i*, whose upper and lower ends *j* are shown in planes radiating from the axis of the shell, 80 (though this direction is not essential.) The inner walls of these flues are circular arcs struck from the axis, or approximately so, of the furnace tube or flue *b*, and their outer walls are circular arcs struck from the axis, 85 or approximately so, of the shell *a*. Within these return-flues *i* water-circulating tubes are sometimes fixed, but none are shown in Fig. 3.

Instead of providing return-flues such as 90 just referred to at each side of the furnace-flue *b* we sometimes (see Fig. 4) arrange the said flue *b* with its axis in a horizontal plane below that containing the axis of the shell *a* and in a vertical plane to one side of that 95 passing through the shell's axis, and we provide at one side of the so-arranged furnace-flue *b* a return-flue *i*, in which there are or are not fixed tubes *k* for the circulation of 100 water.

In one construction of boiler (see Fig. 5) containing two cylindrical plain or corrugated furnace-flues *b*, having their axes in a com- 105 mon horizontal plane above that containing the axis of the shell *a*, we provide three re- turn-flues *i*—viz., a cylindrical return-flue having its axis in the vertical plane contain- 110 ing that of the shell *a*, but located below the furnace-flues *b*, and two side flues, whose inner and outer walls are in circular arcs struck 115 from the axis, or approximately so, of the shell *a*.

The return-flues *i* may be made of plain metal or of metal corrugated transversely to the length of the flue or flues or provided 115 with stiffening-rings or equivalent devices. When the return-flues are not provided with water-circulating tubes, the top and bottom plates of such flue or flues may be of curved 120 section.

In other ways the details of construction may be more or less varied without depart- 125 ing from the characteristic features of the invention. In particular it is to be noted that we do not limit ourselves to furnaces of circular form in cross-section, as our invention may be equally embodied in the con- 130 struction of steam-boilers having furnaces, flues, and combustion-chambers of various other cross-sectional forms, and these may be arranged in any convenient way so long as the return-flues be caused to pass through the cooler parts of the boiler instead of the hotter parts, as is usual in practice.

What we claim is—

1. A steam-boiler comprising a longitudinal shell, one or more main furnace-flues extending longitudinally therethrough, one or more longitudinal return-flues of segmental cross-section located between the main flue or flues and the adjacent side of said shell; and water-tubes extending across said return flue or flues as set forth.
2. A steam-boiler comprising a longitudinal shell, one or more furnace-flues extending longitudinally therethrough, and one or more longitudinal return-flues of segmental cross-section located between the main flue or flues and the adjacent side of said shell, said return flue or flues being arranged below the highest part of said main flue or flues as set forth.
3. A steam-boiler comprising a longitudinal shell, a main furnace-flue extending longitudinally therethrough, a longitudinal return-flue of segmental cross-section located between the main flue and one side of said shell, and water-tubes extending across said

return-flue and secured to walls thereof so 25 as to be in connection at each end with the interior of said shell.

4. A steam-boiler comprising a longitudinal water-containing shell, a main furnace-flue extending longitudinally therethrough, 30 a return-flue of segmental cross-section located between each side of said main flue and the adjacent side of said shell, and curved water-tubes extending across each flue and secured in the top and bottom walls thereof, 35 the circular distance between the top tube-plates of the two return-flues being greater than the length of the longest water-tubes, substantially as described for the purpose specified. 40

Signed at 77 Cornhill, in the city of London, England, this 3d day of June, 1899.

HENRY CHARLES PLATTS.
THOMAS LAWTHER.
